APPARATUS FOR JARRING INGOT MOLDS

Filed April 19, 1929

FIG. 2

FIG. 1

INVENTOR
L. YOUNG

BY J. H. COOK
ATTORNEY

UNITED STATES PATENT OFFICE

LAFAYETTE YOUNG, OF ALTON, ILLINOIS, ASSIGNOR TO LACLEDE STEEL COMPANY,
OF ST. LOUIS, MISSOURI, A CORPORATION OF MISSOURI

APPARATUS FOR JARRING INGOT MOLDS

Application filed April 19, 1929. Serial No. 356,471.

This invention relates generally to jarring apparatus, and more specifically to an improved apparatus for jarring ingot molds, the predominant object of the invention being 5 to provide an improved apparatus of this type whereby a single ingot mold of a plurality of ingot molds mounted on a truck or other support may be jarred or vibrated independently of the associated molds and of 10 the support.

As is very well known in the art of ingot casting, sound ingots which are substantially free from slag inclusions may be obtained by jarring the ingot molds during the operation of pouring the metal into said molds. 15 This jarring has the effect of causing ebullition in the metal within the molds whereby the gases and non-metallic inclusions rise to the top of said body of metal, thus providing 20 for freeing from the body of metal said gases and undesirable non-metallic inclusions, and increasing the density of the resulting ingots.

Prior to this invention a common method 25 of jarring ingot molds involved arranging one or more molds on a suitable support, such, for instance, as an ingot car, and jarring the combined mold or molds and support. This method resulted in a great waste of power, 30 in that the support, which in most cases was of substantial weight, was needlessly jarred. Also, when the support of the ingot molds jarred in accordance with the method just referred to was in the form of an ingot car, the 35 continued jarring of said car reduced the extent of the period of usefulness thereof.

In view of the disadvantages encountered 40 in connection with the method of jarring ingot molds as described above, I have devised 45 the apparatus disclosed herein, which, briefly stated, involves providing means for jarring each individual mold independently of the support and independently of the associated molds. Because of this arrangement, only 50 sufficient power need be exerted against each individual mold to lift said mold and the body of metal therein and jar the same slightly, whereby an economy of power is effected. Also, in the case where less than all of a plurality of molds on a support are being used,

only those molds which are actually receiving metal need be jarred instead of all of said molds together with the support therefor, as heretofore.

Another very important feature of the invention arises from the fact that my improved apparatus provides for elevating an ingot mold and applying sufficient force to said mold while it is so elevated to jar or vibrate same. Because of this arrangement 55 the jarring or vibration of the mold is more effectively performed, because of the absence of supporting elements which would interfere with the jarring or vibration of the mold.

Fig. 1 is a view partly in cross-section and 60 partly in elevation showing my improved jarring apparatus.

Fig. 2 is a side elevation of the apparatus 65 shown in Fig. 1, parts of the air cylinders being broken away to conserve space.

In the drawing, wherein is shown one embodiment merely of the invention, A designates my improved apparatus generally, said apparatus including a support B which in the illustrated embodiment of the invention takes 70 the form of an ingot car, although it may, of course, be in the form of any other type of portable or stationary support which would be suitable for the purpose. The ingot car B is provided with a suitable bed plate 1, 75 suitably supported by side and end members 2, and said side and end members are in turn supported upon under trucks C, which include car wheels 3 which operate on rails 4, so that the ingot car may be transported 80 from place to place. Secured to the bed plate 1 of the ingot car B at the lower face thereof and extended downwardly from said bed plate, is a plurality of guiding members 5, 85 the purpose of which will be subsequently pointed out, the opening through each of said guiding members being alined with an aperture 5' formed through the bed plate 1.

Mounted on the bed plate 1 of the ingot car 90 is a plurality of mold stools 6; each individual one of which is positioned immediately above one of the guiding members 5. Each stool 6 is provided with a downwardly projected extension 7, said extensions being 95 either formed integral with the associated 100

stools or suitably attached thereto. The stools 6 each support an ingot mold 8 of ordinary construction, said ingot molds being loosely supported by the stools and the contact between said elements being sufficiently close to prevent seepage of metal between the molds and the associated stools. The downwardly projected extensions 7 are movably supported in the guiding members 5 and 10 are of such length that the lower ends thereof are located in a horizontal plane slightly below the axles 3' of the trucks of the ingot car, as shown clearly in Fig. 1.

Supported vertically between the rails 4 is a plurality of supporting elements 9 which are so spaced longitudinally of the trackway provided by said rails that the ingot car B may be moved to a position on said rails where the downwardly projected extensions 7 of the 20 stools 6 are aligned vertically with said supporting elements. Each of the supporting elements 9 is provided with an opening 10 formed longitudinally therethrough, in which a ram 11 is arranged for vertical movement, the upper end of said ram being adapted to contact with the lower end of the extension 7 positioned thereabove, as shown in Fig. 1. At the lower end portion of each supporting element 9 is positioned a suitable compressed 30 air hammer 12, which is so associated with the cooperating ram 11 that said ram may be caused to vibrate vertically when the air hammer 12 is operated. 13 designates conductors associated with each of the compressed air 35 hammers 12 for conducting compressed air to and from said compressed air hammer.

The supporting elements 9 are each provided with an elongated opening 14 through which an end portion of a lever 15 passes, 40 said lever at the end thereof which is extended into the supporting element 9 being pivotally secured to the ram 11 within said supporting element as indicated at 16. The levers 15 are all fulcrumed on the shaft or bar 45 17, and at the end of each of the levers opposite to the end thereof which is pivoted to the associated ram 11 said lever is pivoted to a piston rod 18 associated with a piston 19 arranged for reciprocal movement in a compressed air cylinder 20. The compressed air 50 cylinders each have associated therewith a pair of conductors 21, whereby compressed air may be introduced into the cylinder 20 at opposite sides of the piston 19.

55 In the operation of my improved jarring apparatus, the ingot car B with the molds mounted thereon is moved to a position where the extension 7 of the mold stools 6 on said car are positioned immediately above the supporting elements 9. The pouring of the metal into the mold is then commenced, and immediately compressed air is introduced into the cylinders 20 to cause the rams 11 to be elevated. On upward movement of the rams 11 65 the upper ends thereof will contact with the

lower end of the associated extensions 7, whereby these extensions, together with the stools and molds associated therewith, will likewise be elevated until the lower faces of said stools are spaced apart from the top face 70 of the bed plate 1 of the ingot car. When the molds have been so elevated and as the pouring of metal into said mold continues, the compressed air hammers 12 are placed in operation, with the result that repeated intermittent blows are directed by said compressed air hammers against the lower ends of the rams 11. These repeated blows are transmitted by the rams 11 to the extensions 7, and by said extensions to the ingot molds, where- 75 by said molds are jarred or vibrated.

It will be noted when compressed air is introduced into the cylinders 20 at the beginning of the metal pouring operation, that only sufficient pressure need be maintained within 80 said cylinders to lift the weight of the molds plus the weight of the small amount of metal within said molds. Also, it is plain that as the weight of the combined mold and metal increases due to the increased amount of 85 metal within the molds, the pressure within the cylinders may be correspondingly increased to maintain the molds in their elevated positions. It is obvious, therefore, that there is absolutely no waste of power as the 90 pressure within the cylinders 20 may be varied by the operator, so that only sufficient power is present to perform the required work.

Due to the fact that the molds are held in 100 elevated positions by the mechanism associated with the compressed air cylinders, it is plain that the jarring mechanism, the compressed air hammers 12, do not do any great amount of lifting, and hence all of the power 105 exerted by the compressed air hammers is utilized in jarring the molds. Also, because of this jarring action taking place when the molds are balanced in an elevated position, 110 said jarring operation is very effectively performed.

I claim:

1. A jarring apparatus for an ingot mold mounted on a support, comprising means for elevating the ingot mold above its normal support, and means independent of said elevating means for jarring said mold while it is so elevated.

2. A jarring apparatus for an ingot mold mounted on a support, comprising means for elevating the ingot mold above its normal support, and means independent of said elevating means for transmitting repeated light blows to said mold for jarring same the last mentioned means comprising a compressed 115 air hammer.

3. A jarring apparatus for an ingot mold mounted on a support, comprising means including a compressed air cylinder having a reciprocatory piston arranged therein for 120

elevating the ingot mold above its normal support, and means independent of said elevating means for jarring said mold while it is so elevated.

- 5   4. A jarring apparatus for an ingot mold mounted on a support, comprising means for elevating the ingot mold above its normal support, said means including a vertically movable element arranged to contact with a portion of said ingot mold and associated with means for moving said element vertically at will, and means for transmitting repeated light blows to said vertically movable element for the purpose of jarring said ingot mold.
- 10   5. A jarring apparatus for an ingot mold mounted on a support, comprising means for elevating the ingot mold above its normal support, said means including a vertically movable element arranged to contact with a portion of said ingot mold, a pivoted lever to one end of which said vertically movable element is pivotally attached, and means at the opposite end of said lever for raising and lowering the first mentioned end of said lever, and means for transmitting repeated light blows to said vertically movable element for the purpose of jarring said ingot mold.
- 15   6. A jarring apparatus for an ingot mold mounted on a support, comprising means for elevating the ingot mold above its normal support, said means including a vertically movable element arranged to contact with a portion of said ingot mold, a pivoted lever to one end of which said vertically movable element is pivotally attached, and means at the opposite end of said lever including a compressed air cylinder provided with a reciprocating piston cooperatively associated with said lever for raising and lowering the first mentioned end of said lever, and means for transmitting repeated light blows to said vertically movable element for the purpose of jarring said ingot mold.
- 20   7. A jarring apparatus for an ingot mold mounted on a support, comprising means for elevating the ingot mold above its normal support, said means including a vertically movable element arranged to contact with a portion of said ingot mold, a pivoted lever to one end of which said vertically movable element is pivotally attached, and means at the opposite end of said lever including a compressed air cylinder provided with a reciprocating piston cooperatively associated with said lever for raising and lowering the first mentioned end of said lever, and means comprising a compressed air hammer for transmitting repeated light blows to said vertically movable element for the purpose of jarring said ingot mold.
- 25   8. A jarring apparatus for an ingot mold, comprising a support, a guiding member rigidly associated with said support, an ex-

tension on the mold extended through and arranged for vertical movement within said guiding member, means for elevating said mold by applying upward pressure against said extension, and means for jarring said mold by transmitting repeated light blows to said extension. 70

In testimony that I claim the foregoing I hereunto affix my signature.

LAFAYETTE YOUNG. 75
